UNITED STATES PATENT OFFICE

2,129,519

DISPLAY DEVICE

Nelson A. Arend, Cleveland Heights, Ohio, assignor to General Electric Company, a corporation of New York

Application October 19, 1934, Serial No. 749,034

6 Claims. (Cl. 40—130)

My invention relates to display devices for supporting, displaying and advertising articles of merchandise in an attractive manner.

One of the objects of my invention is to provide a device of the type described having practically unlimited flexibility in the number of possible display arrangements.

According to my invention the device consists of a base member provided with a pair of removable posts at the back thereof, the upper surface of the base having arranged thereon a number of slots, a plurality of live sockets for electric lamps, and a number of holes for supporting additional lamps. The removable back posts are provided with two sets of grooves for accommodating various display cards or posters and a number of large headed nails or screws are arranged on these back posts for supporting key-hole slotted side pieces. The slots on the base may be used for holding various display cards or reflector cards. The number of permissible display arrangements which may be achieved by using various combinations of these features is almost unlimited.

Further features and advantages of my invention will appear from the following detailed description of species thereof and from the drawings.

In the drawings, Fig. 1 is a front perspective view of a display device comprising my invention; Fig. 2 is a rear perspective view thereof; Fig. 3 is a perspective view of the base portion of the device; Fig. 4 is a plan view of the device; Fig. 5 is an elevation of the inside face of the right hand upright post seen in Figs. 1-3; Fig. 6 is a diagrammatic representation of a wiring diagram for the electrical sockets in the device; Fig. 7 is a perspective view of a slightly modified base made of sheet metal; Fig. 8 is a perspective view of one possible display arrangement; Fig. 9 is a perspective view of a portion of the rear of an upright post and a side piece of Fig. 8 showing the method of mounting the said side piece on the post; and Figs. 10 to 12 are perspective views of other possible display arrangements.

Referring to Figs. 1-4, the device comprises a hollow base member 10 having an upper surface 11 provided with three holes 12 extending in a line across the front thereof and located in the middle and at each side respectively. Electrical sockets 13 are disposed in the said holes 12 for the reception of incandescent lamps. Additional holes 14 are provided in line with the holes 12 for supporting additional lamps, there being a pair of holes 14 between the center hole 12 and each of the outside holes 12. Three slots 15, 16, 17 are provided in front and at each side respectively of the three holes 12 for holding display cards or reflector cards. The slots 16, 17 at each side of the holes 12 may be arranged

parallel to the sides of the base 10 as shown. Two pairs of slots 18, 19 are arranged behind the row of holes 12, 14 in rows parallel to the front and back sides of the base for the reception of various interchangeable cardboard displays. 5 A space may be provided between the rear edge 20 of the upper surface 11 and the back side 21 of the base 10. A pair of partitions 22 (Fig. 3) are mounted in the back of the base 10 at each side thereof and parallel to the sides. 10

A pair of removable upright posts 23 are mounted at the back and one at each side of the base 10 in the sockets 24 (Fig. 3) formed by the back side 21, the rear edge 20 of the upper surface 11, the partitions 22, and the sides of said base. The inside opposing faces of said posts 23 are each provided with an elongated groove 25 extending from the top of the post to the upper surface of the base 10, said grooves being adapted to receive a cardboard back-piece or background panel to which interchangeable paper display posters may be attached by means of spring clips or by pasting. Interchangeable cardboard displays may also be accommodated in these grooves. An additional set (three pairs 25 being shown) of grooves or slots 26, 27, 28 is provided on the said inner faces of the posts 23, the said slots being spaced along the said posts in opposed pairs each adjacent a groove 25. The said pairs of slots 26, 27, 28 are adapted to receive the ends of cardboard strips carrying advertising matter. Short grooves 29 (Fig. 5) are provided at the top of each of the posts 23 to receive the ends of a cross-piece 30. The backs of said posts 23 are provided with large-headed 35 nails or screws 31 (Figs. 2 and 5) which are adapted to support various key-hole slotted side pieces.

A portion of the back of each of the partitions 22 may be cut back to form a slot 32 (Fig. 3) 40 so that the upright posts 23 may be withdrawn and cardboard displays inserted in the slots if desired.

The rear edge 20 of the upper surface 11 of the base 10 is cut back at the middle as shown 45 at 33 to form an opening in said surface, and a lamp 34 and reflector 35 are disposed therebelow, within the base 10, to illuminate display cards arranged in the upright posts 23 or in the slots 32. The said lamp 34 is mounted in a socket 36 which 50 is supported by a bracket 37 (Fig. 4) which may be mounted in any convenient place such as on the inside of the upper surface 11, or on the back wall of the base.

As illustrated in Fig. 6, the sockets 13 and 55 socket 36 are preferably connected electrically in multiple so that lamps mounted therein may be illuminated singly or in any desired combination.

The base appears substantially as shown in 60

Figs. 1-4 when constructed of wood. However, it may, of course, be made of sheet metal, in which case it is made as shown in Fig. 7. The base 10' in Fig. 7 is substantially identical in appearance to the base in Figs. 1-4 except that the space in the latter base between the edge 20 of the upper surface and the back wall 21 is not provided. Instead, an opening 33', similar to the opening 33 is provided at the rear and middle 10 of the upper surface 11'. A hole 24' is provided in said surface at each of the back corners to receive the end of a post 23.

Figs. 8 to 12 show only a few of the great number of display arrangements which may be achieved with this device. In Fig. 8, incandescent lamps 38 are mounted in the sockets 13 in the holes 12 and additional lamps 39 are mounted in the holes 14. Cardboard strips 40 carrying advertising matter have their ends inserted in the 20 pairs of slots 26, 27, 28 in the posts 23, the said strips 40 being bowed out as shown in the drawings. Side pieces 41, representing the outlines of a Christmas tree, are mounted on the upright posts 23. The said side pieces 41 are mounted 25 on the pins or nails 31 on the back of the posts 23 by means of key-hole slots 42 as illustrated in Fig. 9.

In Fig. 10, the three lamps 38 are used in conjunction with individual reflectors 43 to illuminate 30 a poster consisting of an illustrated paper sheet (not shown) mounted on a background panel consisting of a cardboard sheet 44 located in the grooves 25 in the upright posts 23. The paper poster may be clipped to the cardboard sheet 44 at 35 the top and bottom by clips 45. The poster may be further illuminated by the lamp 34 (Fig. 4) in the base 10. Various types and designs of side pieces may also be arranged on the backs of the posts 23 together with or without the center poster on the cardboard sheet 44.

Fig. 11 represents a scenic display comprising a poster sheet 45' clipped onto the cardboard sheet 44 (not shown), and removable cardboard scenic pieces 46, 47, 48 having tabs which are inserted 45 in the slots 15, 18, 19 (Figs. 1 and 4) respectively. The display may be illuminated by lamps 34 and 38 (Figs. 4 and 8).

Fig. 12 represents an arrangement in which the upright posts 23 have been removed and a cardboard display piece 49 has been inserted in the slots 32 at the back of the base 10. Another display piece 50 extends across the front of said base 10, being held by means of tabs thereon inserted in the slots 15 (Figs. 1 and 4). This display may also be illuminated.

It will be apparent from a viewing of Figs. 8 to 12 that the number of different possible arrangements of displays is practically unlimited, the said figures illustrating only a few of them.

What I claim as new and desire to secure by Letters Patent of the United States is:

1. A display device comprising a hollow base, a pair of spaced upright posts mounted at the back of said base, a groove in each of the opposing inner faces of said posts extending from the top thereof substantially to the upper surface of said base and adapted to receive a background panel, a plurality of pins secured to and spaced along the back surfaces of said posts, removable side pieces, supported by said pins the upper surface of said base having an opening at the rear and substantially at the middle thereof, and a lamp in said base below said opening adapted to illuminate said background panel.

2. A display device comprising a hollow base, a pair of spaced upright posts mounted at the back of said base, a groove in each of the opposing inner faces of said posts extending from the top thereof substantially to the upper surface of said base and adapted to receive a background panel, a plurality of pairs of opposed relatively short slots located at spaced intervals along said posts adjacent the edges of said grooves and adapted to receive the ends of cardboard strips, the upper surface of said base having an opening at the rear and substantially at the middle thereof, and a lamp in said base below said opening adapted to illuminate said background panel.

3. A display device comprising a hollow base, a pair of spaced upright posts mounted at the back of said base, a groove in each of the opposing inner faces of said posts extending from the top thereof substantially to the upper surface of said base and adapted to receive a background panel, the upper surface of said base having an opening at the rear and substantially at the middle thereof, a lamp in said base below said opening adapted to illuminate said background panel, and a plurality of rows of slots in the said upper surface adapted to receive interchangeable cardboard displays.

4. A display device comprising a hollow base, a pair of spaced upright posts mounted at the back of said base, a groove in each of the opposing inner faces of said posts extending from the top thereof substantially to the upper surface of said base and adapted to receive a background panel, a plurality of pairs of opposed relatively short slots located at spaced intervals along said posts adjacent the edges of said grooves and adapted to receive the ends of cardboard strips, and a lamp mounted in said base for illuminating said background panel.

5. A display device comprising a hollow base, a pair of spaced upright posts mounted at the back of said base, a groove in each of the opposing inner faces of said posts extending from the top thereof substantially to the upper surface of said base and adapted to receive a background panel, a plurality of pairs of opposed relatively short slots located at spaced intervals along said posts adjacent the edges of said grooves and adapted to receive the ends of cardboard strips, a plurality of electric lamp sockets disposed in the top of said base along the front edge thereof for receiving lamps to illuminate said background panel, and a plurality of slots in the said top of said base located adjacent said sockets for mounting interchangeable display or reflector cards in front of said lamps.

6. In a display device, a hollow substantially rectangular base having means at the rear corners for receiving upright posts adapted to support a background panel, an opening in the upper surface of said base at the rear thereof, a lamp disposed below said opening for illuminating said background panel, a plurality of sockets for electric lamps located in said upper surface along the front edge thereof, a plurality of slots in said upper surface located adjacent said sockets for mounting interchangeable display cards or reflectors in front of the lamps therein, and a plurality of rows of slots for receiving display cards located in said upper surface between said sockets and said post receiving means.
